A. W. Gray,

House Power.

No 15,693.

Patented Sep. 9, 1856.

UNITED STATES PATENT OFFICE.

A. W. GRAY, OF MIDDLETOWN, VERMONT.

LINK OF HORSE-POWERS.

Specification forming part of Letters Patent No. 15,693, dated September 9, 1856; Reissued July 1, 1862, No. 1,322.

To all whom it may concern:

Be it known that I, A. W. GRAY, of Middletown, in the county of Rutland and State of Vermont, have invented a new and 5 Improved Horse-Power; and I do hereby declare that the following is a full and exact description thereof, reference being had to the accompanying drawings, making a part of this specification, Figure 1, being a 10 longitudinal, vertical section of the horse power; Fig. 2, a transverse section thereof in the line $x x$, Fig. 1; Fig. 3, a longitudinal section, in the line $y y$, Fig. 1; Fig. 4, perspective of one of the lags, with its 15 links attached; Fig. 5, longitudinal section of one of the links.

Like letters designate corresponding parts in all the figures.

My improvements relate to the mode of 20 constructing and arranging the endless chain of lags, whereby greater cheapness, greater strength, less weight, and less friction, are secured.

The links G, G, which unite the lags 25 H, H, are made of strong sheet iron in the following manner:—A piece d , (Fig. 5,) is bent into an oblong, rectangular form, so as to furnish a mortise for the reception 30 of a tenon on the end of the lag. Another strip of sheet metal is bent in such a manner that the upper side shall be straight and fit the lower side of the mortise piece d , to which it is riveted; while the lower side is formed into corrugations c , of such 35 form as to constitute a series of regular cogs, from end to end, the two end corrugations inclosing a round aperture, and projecting sufficiently beyond the lag, or mortise, portion d , to receive the connecting 40 rods b , on which the links turn, and are joined together; all substantially as represented in the drawings.

The whole link is readily made by suitable dies, or swages, and is exceedingly 45 cheap, light and strong.

The corrugations c , c , of the series of links, constitute double racks on the inner side of the endless platform of lags, which gear into cog-wheels E, E, on the driving 50 shaft D. Said cog-wheels should be about twice as thick as the links are wide, since the links of successive lags are placed side by side; that is, those of one lag, are placed inside of those of the adjoining lags, and 55 vice versa, as shown in Fig. 3. The mor-

tises d , d , of the links, are made long enough to receive the full width of the lags; but the width of the mortises is only sufficient to receive a portion of the thickness of the lags. The tenons are formed by simply 60 sawing into the ends of the lags, so as to leave the proper thickness to insert into the mortises, the saw-kerf being sufficiently wide to receive the thickness of the metal of the link. The driving shaft D, is generally placed under a straight or plain portion of the endless platform, as represented, whereby wider lags may be employed, and the links pass more freely over the cog-wheels E, E. 65

Friction rollers a , a are placed upon the ends of the connecting rods b , b . These rollers, instead of being entirely perforated, and passing the ends of the rods b , b , through them, are simply provided with 70 holes bored only partly through them, as represented. They are then simply slipped loosely upon the ends of the rods; and are kept in place by the tracks A, B, on which the endless platform runs, and by the timbers I, I, of the frame, which incloses them. Thus they are more readily and cheaply 75 made than usual, and running freely, obviate all binding, which often causes endless-chain horse powers to turn with considerable 80 unnecessary friction and impediment. 85

The advantages of a horse-power thus constructed, are principally, its lightness; the light but strong sheet-iron links very much diminishing the weight of the endless-platform, thus not only diminishing the 90 whole weight of the machine, but increasing the effective power thereof; readiness and cheapness of construction; lessened friction; and equal or superior strength. 95

What I claim as my invention and desire to secure by Letters Patent, is—

Constructing the links composing the endless chain, of corrugated sheet-metal, so that the corrugations shall serve both as 100 hinges for connecting the links and as cogs for gearing into the cog-wheels on the driving shaft, substantially as herein specified.

The above specification of my new and improved horse power, signed by me this 105 fifth day of March A. D. 1856.

ALBERT W. GRAY.
